PAGE 2

Fig. 2

Fig. 4

Fig. 3

FIG. 1 is a side elevation of a motor coach showing my new design;

FIG. 2 is a side elevation of the opposite side thereof;

FIG. 3 is a front end view thereof; and

FIG. 4 is a rear end view thereof, all showing my new design.

The design is characterized by the relatively short forwardly projecting front portion of the body adjacent to the entrance door, and which is stepped down and extends forwardly from the main body of the motor coach, and by the forwardly inclined portions above the windshields, and by the recessed front and rear lights, and the elongate Z-shaped streamer decorations on each side of the body, and the eagle depicted on the front and rear ends.

I claim:

The ornamental design for a motor coach, substantially as shown and described.
